UNITED STATES PATENT OFFICE.

GEORGE E. THRALL, WILLIAM S. THRALL AND PERRY O. THRALL, OF WASHINGTON,
DISTRICT OF COLUMBIA.

SCAFFOLD.

1,113,509.

Specification of Letters Patent. Patented Oct. 13, 1914.

Application filed July 8, 1914. Serial No. 849,778.

To all whom it may concern:

Be it known that we, GEORGE E. THRALL, WILLIAM S. THRALL, and PERRY O. THRALL, citizens of the United States, residing at 5 Washington, in the District of Columbia, have invented certain new and useful Improvements in Scaffolds, of which the following is a specification.

This invention relates to scaffolds, and 10 more particularly to means for supporting a ladder in upright position to adapt it to sustain scaffolding in working position.

The primary object of the invention is, to 15 provide novel means for supporting ladders, or like vertical scaffold supports in proper juxtaposition to a window, a column or other support.

The invention also includes means for 20 securing planks or staging to the rounds of a ladder.

The construction of the improvement will 25 be fully described hereinafter in connection with the accompanying drawing, which forms a part of this specification, and its features of novelty will be set forth and defined in the appended claims.

In the drawing:

Figure 1 is a top plan view of a ladder clamp embodying the invention. Fig. 2 is a 30 fragmentary perspective view showing the clamp in position upon a window frame. Fig. 3 is a top plan view of a modified construction of the device adapted for use in connection with a column or other circular support. Fig. 4 is a side elevation of a portion 35 of a ladder showing the ladder brace and staging partly in section, and Fig. 5 is a detail longitudinal section of the board shown in Fig. 4 with its U-shaped securing 40 clamp.

The reference numeral 1 designates a window frame of the usual construction, and 2 an ordinary ladder supported in front of the window in upright position by the 45 novel means shown, comprising a clamp consisting of two parallel arms 3 from the inner ends of which project diverging arms 4 connected by a horizontal brace 5 and having their inner ends 6 in parallel relation 50 to be clamped against the inner sides of the window frame as shown in Fig. 2 by suitable means, the means here shown comprising two extensible bars 8 having their inner ends 9 screw threaded for attachment to a

turn-buckle 10. The outer ends 11 of the 55 bars 8 are squared to extend through correspondingly shaped guides 12 formed in the flattened ends 6 of the arms 3, and adapted to be automatically secured thereto by clamping devices as shown at 13. The 60 parallel outer ends of the arms 3 embrace the ladder 2 on opposite sides thereof, and are detachably connected to the ladder by cross-bolts 14.

The board or staging 15 rests upon the 65 rounds 16 of the ladder as shown in Figs. 4 and 5, and the ends of the board are secured upon the rounds by U-shaped clamps 17 extending through openings in the board, and embracing the ladder round as best shown 70 in Fig. 5.

It will be apparent that the turn-buckle 10 permits of the adjustment of the bars 8 to fit windows of different width, and that the device is readily detachable from both 75 the ladder and window-frame.

Fig. 3 shows a modified embodiment of the invention in which two semi-circular clamping arms 18 and 19 are employed to adapt the device to be secured upon a round 80 column or like circular support, instead of to the sides of a window frame. The bars 8^a are formed integral with the member 19 and are recessed as at 20 to receive the ends 21 of the other clamping member 18, said 85 ends being detachably connected to the bars 8^a by securing devices 22.

The improvement affords means for readily building a scaffold or staging wherever required, and by reason of the ready 90 removability of all of the securing devices the scaffolding may be quickly taken down.

Having fully described our invention, what we claim and desire to secure by Letters Patent is:

95

1. A ladder support for scaffolding comprising a pair of parallel arms, having diverging inner ends adapted to be secured to a support, and means for detachably securing said arms on opposite sides of a ladder. 100

2. The combination with a window frame and a ladder, of a pair of parallel arms embracing opposite sides of the ladder, and having diverging inner ends, longitudinally adjustable bars for clamping said diverging 105 members to the sides of the window frame, and means for securing said parallel arms together.

3. The combination with a window frame and a ladder, of a clamping device comprising parallel arms embracing opposite sides of the ladder and having diverging inner ends provided with guides, longitudinally adjustable bars extending through said guides, devices for securing said bars within said guides, and means for detachably securing the arms together.

In testimony whereof we affix our signatures in presence of two witnesses.

GEORGE E. THRALL.
WILLIAM S. THRALL.
PERRY O. THRALL.
